UNITED STATES PATENT OFFICE.

NATHANIEL D. STEVENS, OF HAZLETON, PENNSYLVANIA, AND LOUIS H. HOSBEIN, OF CHICAGO, ILLINOIS, ASSIGNEES TO M. H. DETRICK COMPANY, OF CHICAGO, ILLINOIS, A CORPORATION OF ILLINOIS.

FURNACE-ARCH CONSTRUCTION.

Application filed November 9, 1920. Serial No. 422,775.

This invention relates generally to furnace arch construction, and in certain features pertains particularly to ignition arch constructions especially adapted for use in 5 furnaces equipped with over-feed or traveling grate stokers.

A general object of the invention is the provision of a furnace arch construction which is particularly qualified to withstand 10 the destructive influences to which such structures are subjected in use, and which, when employed in ignition arches, is adapted to contribute effectively to early ignition of fresh fuel and to the promotion of combustion 15 within the furnace.

Another object is the provision of an arch construction which effectively fulfills the requirements mentioned and which is adapted to be installed with facility and admit of 20 repair, particularly with respect to the renewal or replacement of the refractories, with convenience and without requiring extensive dismantling of associated parts.

Still another object of the invention is 25 the provision of an arch construction possessing the characteristics above mentioned and which may be installed in furnaces not designed particularly therefor, and which may be supported without depending upon 30 the furnace walls as the load carrying members.

Yet another object is the provision of an arch construction particularly adapted for 35 the support of an apron wall in association therewith and in such fashion that the shifting of the arch refractories incident to expansion or contraction of the structure from 40 temperature changes will not displace the wall or open up joints between it and the associated arch portions.

Yet another object is the provision of a construction by virtue of which the arch and the associated apron wall may be supported in association with other parts of 45 the structure, such as a movable gate for controlling the feed of fuel, without hampering or imposing limitations on the operation or adjustment of such associated parts.

Yet another object of the invention is the 50 provision of an improved element of furnace arch construction, in the nature of a specially formed refractory or tile having features which render possible the construc-

tion of an arch of advantageous form and 55 flexibility.

Other and further objects and advantages of the invention will be pointed out or indicated hereinafter, or be apparent to one skilled in the art upon an understanding of the invention or its employment in practice. 60

In the accompanying drawing forming a part of this specification, is illustrated one form of arch construction in which the invention may be embodied, but it is to be understood that this is presented for purpose of illustration only, and is not to be given any interpretation having the effect of limiting the claims short of the true and most comprehensive scope of the invention in the art. 70

In the drawings:

Fig. 1 is a longitudinal vertical section through a portion of a chain grate stoker furnace equipped with an ignition arch construction in which our invention is embodied; 75

Fig. 2 is a transverse vertical section of the furnace, as on line 2—2 of Fig. 1, showing the roof arch in section and the ignition arch in elevation with certain intermediate 80 portions removed;

Fig. 3 is a perspective view of one of the brick supporting structures and its suspension plate;

Fig. 4 is a transverse section of said brick 85 supporting structure, as on line 4—4 of Fig. 3;

Figs. 5 and 6 are perspective views of special wedged shaped refractories or tile constituting subject matter of our invention. 90

As is well known in the art, in various types of over-feed stokers and the so-called chain-grate stokers, fuel is fed to the fuel bed in such fashion that it comes into the furnace at the marginal portion thereof. 95 This fresh fuel, of course, is cool, and before it will ignite, its temperature must be raised to the ignition point. Efficient operation demands that this be accomplished as quickly as possible. Ignition arches have been constructed in various fashions for the purpose of attaining this result. One of the important advantages made possible by the present invention resides in the fact that by our improved construction, not only is the ignition of the fresh fuel attained efficiently and 100

quickly, but also the combustion efficiency of the furnace is increased and the arch is effectively safe-guarded against too rapid disintegration from the normal condition existing within the furnace. We accomplished these results by the provision of a construction which renders it practicable to bring the forward extremity of the ignition arch down to a point quite close to the surface of the fuel bed where the fresh fuel is fed thereto, while positioning the portion of the arch above the ignited portions of the fuel bed at such a distance therefrom and in such a relationship thereto as to avoid, to an advantageous extent, the destructive influences of the heat and the products of combustion from the burning fuel. At the same time, the construction permits the reduction of cold space within the furnace without limiting the combustion space desirable for the complete combustion of the volatiles or suspended constituents in the combustion gases, and accommodates a maximum reflection of radiant heat onto the entering fuel below the ignition arch. The invention is not limited for its advantages to employment in ignition arches, however, as it possesses certain structural features which contribute a desirable flexibility in portion of refractory arch structure where the arch changes direction, maintaining close joints between the component refractories and affording uniform protection for the metallic members whereby they are supported.

Referring to the particular example illustrated in the drawings, let it be understood that the numeral 10 designates the side walls of the furnace, and 11 the fuel hopper which is located exteriorly at the front of the combustion chamber and from which the traveling chain grate 12 feeds the fuel into the furnace chamber under the fuel gate 9, in the customary manner. The numeral 13 designates the roof arch or combustion arch of the furnace, which is located a suitable distance above the chain grate to afford the desired volume within the combustion chamber to permit the proper admixture of air with the volatiles given off from the fuel and promote combustion thereof. The numeral 14 designates generally the ignition arch which is located at the front of the furnace with its lower end adjacent the fuel inlet and in association with the fuel gate. This ignition arch is carried on a plurality of brick supporting frames, preferably of cast-iron, which are arranged in collateral relationship across the front of the combustion chamber. Each of these frames is suspended by means of a suspension plate 14^a from a girder or beam 15 which extends transversely across the forward portion of the combustion chamber, being supported either on the side wall 10 or on other supporting members. Each of these frames in

the form here shown, comprises a webbed body portion having an upper horizontally flanged portion 17, a vertical front portion 18, and a curved or convex rear portion 19. The convex portion 19 is provided at its rearward margin with laterally extending flanges 20 which take the arcuate form of the portion 19, and from the lower end of these flanges depends a stop member 21. The front vertical portion 18 is provided on each side thereof with spaced vertical flanges 22, which terminate at their lower ends in a horizontal flange 23. Suspended on the arcuate flanges 20 of each of the frame members, is a series of wedge shaped refractories 24, which are formed with the T-shaped slots 25 approximately at the middle portion of their narrower ends, said slots receiving the flanges 20 and a portion of the web 19, so that the refractories are retained thereon with a limited freedom of individual movement. It will be observed that these wedge shaped refractories 24 are of a form wherein the broader end face extends at approximately a right angle from one of the converging faces, so that the opposite converging face meets the broader end face at an acute angle. By virtue of this form of the wedge shaped refractories, they may be arranged so as to vary the curvature of the arch surface which is formed by their broader end faces. The refractories 24 are slipped on to the flanges 20 at the upper end of the latter, the first refractory applied being slid down into contact with the stop member 21, and the succeeding refractories being slipped down into abutting contact with one another in series. The lateral faces of the refractories on adjacent frame members make contact, so that when all are assembled the structure provides a convex refractory arch extending across the front of the furnace chamber and terminating at its lower end adjacent the fuel gate and close to the fuel inlet. By the assembly of the wedge shaped refractories in the manner illustrated, the uppermost one presents its upper face in a substantially horizontal disposal at some distance below the roof arch 13. The intervening space is filled by an apron wall built up of refractories 26, which are supported on the uppermost wedge shaped refractories 24, and the joint between the top of this apron wall and the roof arch is filled with a suitable refractory joint material. It will be observed that on each of the frame members, the web shaped refractories 24 as well as the apron wall refractories 26 are supported in position by the stop member 21, which prevents the lowermost refractories 24 from being displaced forwardly, thereby safeguarding the adjustable fuel gate from pressure from the refractory arch. In order to afford a covering protection for the stop member 21, the refractories may be provided in one of

the converging faces with a depression 28, as illustrated in Fig. 5, into which the stop member fits so that the face of the refractory may come out approximately flush with the 5 outer surface of the stop member.

It will be observed that the construction provides a refractory arch in which each of the component refractories has but a single face exposed to the fire within the combustion chamber, which face is of relatively limited area. By virtue of this feature, the destructive influences of the high furnace heat and the erosion from the furnace gases and slag are minimized, with the result that 10 the arch does not wear out so rapidly and the wear is more uniform over its surface and not so likely to be localized. Thus, not only is the life of the arch as a whole increased, but the likelihood of having to shut down the furnace for repair of a badly worn spot is substantially reduced. When embodied in an ignition arch, this construction provides a refractory heat reflecting wall with a heat resisting and reflecting surface 15 close to the entering fuel and arranged to direct reflected heat on to it. At the same time, this depending arch does not overhang the fuel bed in such fashion as to baffle or mask the reflection of heat from the top arch on to 20 the entering fuel, but tends to aid in the concentration of heat on the fuel bed immediately inside the fuel inlet. This is of particular importance in instances where it is desirable that the ignition arch extend for a 25 substantial distance into the upper portion of the front of the combustion chamber, where it exercises an important function in reducing the space over the fuel inlet, which otherwise would be relatively cold and thus 30 hinder the quick ignition of the entering fuel. By virtue of the manner in which the wedge shaped tile are constructed, they are 35 susceptible of a limited freedom of movement relative to one another both laterally, forwardly, backwardly and outwardly, the engagement of the tile with the supporting frames permitting them individually a certain extent of rocking movement in those directions. This assures a close fit between the 40 tile at all times and permits them to accommodate themselves to expansion and contraction of the structure resulting from temperature changes, without imposing injurious 45 stresses on them or on the supporting members.

Between the flanges 22 of juxtaposed frame members are slid tiers of brick 29, which find support on the horizontal flanges 23. These tiers of brick form a vertical front 50 wall which prevents coal from the coal hopper being pushed back on to the outer ends of the refractories 24, and maintains an open space for the circulation of air over the outer ends of those refractories and the 55 frame members. This is of distinct impor-

tance in prolonging the life of the refractories, as by this exposure to air which is afforded to each of them by this construction, an additional safeguard is afforded against their destructive over-heating and dissipation of heat from the metallic frame members is promoted.

When it becomes necessary to replace any of the refractories, the apron wall refractories 26 are first removed, after which the 75 wedge shaped refractories may be moved upwardly on the flanges 20 and disengaged therefrom at the upper end. Thus replacement of refractories on any of the frame members may be made without the necessity 80 for dismantling refractories from associated frame members.

As the arch expands or contracts longitudinally incident to temperature changes, the aggregate movement resulting therefrom is imparted to the apron wall in a vertical direction without relative displacement of the wall and the arch refractories which support it. Consequently, expansion or contraction of the arch does not have the effect 85 of displacing the apron wall into the furnace, or of dislocating its support or of opening the joint between the arch and wall.

We claim:

1. In a furnace having a fuel inlet at a margin of the grate, an ignition arch arranged above the margin of the grate at which fuel is introduced, said ignition arch comprising a series of spaced-apart depending frame members having a convex inner portion rising abruptly from the lower end, such convex portion having a laterally projecting flange for a part of its length, and a series of wedge-shaped bricks having in their smaller ends recesses accommodating the said flange to sustain said bricks in abutment with one another.

2. In a furnace having a grate, an ignition arch arranged above the portion of the grate at the fuel inlet, said ignition arch comprising a series of frames each having a convex inner portion rising abruptly from its lower portion, such convex portion having a succession of angularly related longitudinal flanges, and series of wedge-shaped bricks having in their smaller ends recesses accommodating the said flanges to sustain said bricks in abutment one with another.

3. In a furnace having a grate and a main arch overhanging the grate, an ignition arch arranged above the margin of the grate at which fuel is introduced, said ignition arch comprising a series of laterally associated frames each having a convex inner portion rising abruptly from its lower end toward the main arch, and having also a vertical front portion, such convex and vertical portions having marginal flanges, series of wedge-shaped bricks having in their smaller ends recesses accommodating the flanges of

the convex portion and disposed in close lateral relationship, and a series of bricks sustained by the flanges of the vertical portion.

- 5 4. In a furnace having a grate and a main arch overhanging the grate, an ignition arch arranged above the portion of the grate at which fuel is introduced, said ignition arch comprising a girder arranged at a margin 10 of the main arch, a series of laterally associated frames secured to and depending from said girder, each of said frames having a convex inner portion rising abruptly from its lower end toward the main arch, 15 and having also a front vertical portion, such convex and vertical portions having marginal flanges, a series of wedge-shaped bricks supported by said convex portions and arranged in close lateral relation to one 20 another, a series of bricks imposed on said wedge-shaped bricks and built up to the main arch, and a series of bricks retained by the flanges of the vertical portion.

5. In a furnace, an ignition arch comprising a plurality of frames having their lower extremities disposed adjacent the fuel inlet and each including a tile supporting portion extending inwardly and upwardly from its lower extremity, said tile supporting portion carrying tile retaining members, and wedge-shaped tile connected at their smaller ends with said retaining members to retain juxtaposed tile with their converging faces in abutment, the larger end surfaces of said tile forming a fire resisting wall extending first inwardly and then abruptly upwardly from the fuel inlet.

6. In a furnace arch construction, the combination of a plurality of collaterally disposed frame members, each including an inwardly and upwardly extending arch supporting portion and an upwardly extending wall supporting portion, and brick retained in association by said respective portions to 45 constitute a wall portion and an arch portion of the furnace.

7. In a furnace, an ignition arch comprising a plurality of collaterally disposed frame members having their lower extremities disposed adjacent and above the fuel inlet, each of said frame members including an inwardly and upwardly extending part carrying tile retaining members, a plurality of wedge shaped tile engaged at their narrower ends with said retaining members, the tile on each frame member being disposed with the converging faces of juxtaposed tile in abutment whereby the exposed end faces of the tile form a substantially regular convex arch surface extending inwardly and upwardly from the fuel inlet.

8. As an article of manufacture, a furnace arch portion consisting of refractory tile having parallel lateral faces and converging 65 front and rear faces all of substantially

equivalent length and adapted for surface contact with juxtaposed tile, said tile being provided at the middle portion of their narrower ends with slots extending from front to rear with constricted upper portions 70 forming over-hanging support engaging members whereby the tile may be supported in alignment on a bar with their converging faces in contact.

9. In a furnace, a fire box arch, a transverse suspension beam arranged in front of said arch, and a convex arcuate ignition arch made up of refractory tile suspended from said beam at the front of the fire box chamber, each of said tile presenting but a single 80 face within the combustion chamber.

10. In a furnace, a roof arch, a transverse suspension beam arranged in front of said arch, a convex arcuate ignition arch suspended from said beam at the front of the 85 furnace chamber, and an apron wall resting on the ignition arch and extending between the same and the roof arch to form the upper portion of the front of the furnace chamber.

11. In a furnace, a roof arch having a series of transverse suspension beams overlying the arch refractories and supporting the same, a transverse suspension beam arranged in front of said roof arch, and a 95 convex arcuate ignition arch suspended from said beam at the front of the furnace chamber, said ignition arch curving inwardly and abruptly upwardly from the fuel inlet to accommodate the reflection of heat from the 100 roof arch onto entering fuel.

12. In a combustion furnace having a vertically extending wall portion, an arch construction including a substantially horizontally extending refractory roof arch portion, 105 a plurality of refractories supported adjacent the vertical wall portion to form an inwardly and upwardly extending refractory arch portion below the roof arch portion, and a plurality of vertically associated refractories supported upon the inwardly and upwardly extending arch portion and forming a vertically extending wall closing the space between the same and the roof arch portion.

13. In a furnace, an arch construction comprising a suspension beam, a metallic frame member secured thereto and depending below the same, and a tier of wedge-shaped refractory bricks slotted to straddle 110 said frame member, and secured thereto.

14. In furnace construction, the combination with a substantially vertical wall portion and a substantially horizontal refractory arch portion, of a plurality of tile supporting members disposed adjacent said portions, and a plurality of wedge-shaped refractories supported on said members with their lateral faces in contact and with their broader end faces forming a convex arcuate 125 portion.

wall surface between the vertical wall portion and the horizontal arch portion.

15. In furnace arch construction, a refractory tile for suspension on a frame member having a stop flange, said tile being of wedge shape with converging front and rear faces and parallel side faces and being provided with a slot extending from front to rear for accommodation of the frame member, said tile being provided adjacent said slot with a depression in one of its converging sides for accommodation of the stop flange of the frame member.

16. In furnace arch construction, the combination of a beam disposed above a portion of the furnace chamber, collaterally arranged frame members depending from the beam, wedge-shaped tile suspended from said frame members with their broader ends toward the furnace chamber and their lateral faces juxtaposed, to form an upwardly deflected convex refractory arch portion, refractories supported on the upper tile to form a vertical wall portion as an upward continuation from said convex portion, and stop members on said frame members contacting the lower terminal wedge-shaped tile.

17. As an article of manufacture, a structural element for furnace arches, consisting of a wedge-shaped tile of refractory material having parallel lateral sides and converging front and back sides, said tile being provided at the narrower end with a medial T-shaped slot opening at the converging sides and across the top to provide oppositely overhanging shoulders whereby the tile may be supported with its front and back sides in contact with those of similar tile.

18. As an article of manufacture, a structural element for furnace arches, consisting of a wedge-shaped refractory tile having parallel lateral sides and converging front and rear sides, and a broader end face meeting one of said last mentioned sides at approximately right angles, said tile being provided in its narrower end with a medial inverted T-shaped slot opening at the front and back sides.

19. In furnace construction, the combination of frame members collaterally disposed along a side of the furnace chamber, an up-

right wall portion supported on said frame members, and a convex refractory arch portion supported on said frame members 55 extending inwardly and upwardly between said wall portion and the combustion chamber.

20. In furnace construction, the combination of frame members disposed collaterally 60 along a side of the furnace chamber, a convex refractory arch formed of refractories retained by said frame members, and an upright wall portion built upon said arch portion with its inner surface arranged as a 65 continuation from the arcuate surface of the arch.

21. A frame member for furnace arch construction comprising a casting having a web portion with an arcuate tile supporting 70 flange extending at an angle therefrom and provided at an upper margin with means for engagement by a supporting member, whereby the casting may be suspended from the top with the arc of the flange in a vertical plane. 75

22. In furnace construction, collaterally arranged frame members, wedge shaped tile suspended thereon with their broader end surfaces exposed within the furnace chamber and their narrower end surfaces exposed outside the furnace chamber, and a wall spaced from the outside ends of the refractories to afford an intervening air duct for circulation of air across said ends of the refractories. 80 85

23. In a furnace, an arch construction comprising a metallic frame member, and a tier of wedge shaped refractory bricks slotted to straddle said frame member and secured thereto, the wider end surfaces of said wedge shaped bricks forming a convex arch portion within the furnace chamber. 90

24. In a chain grate furnace, the combination with a roof arch over the combustion chamber, of a convex ignition arch suspended at the front of the roof arch and presenting a refractory surface curving inwardly and upwardly from the fuel inlet to accommodate and concentrate heat reflected from 95 the roof arch onto fuel on the grate at the fuel inlet. 100

LOUIS H. HOSBEIN.

DISCLAIMER

1,628,284.—*Nathaniel D. Stevens*, Hazleton, Pa., and *Louis H. Hosbein*, Chicago, Ill. FURNACE-ARCH CONSTRUCTION. Patent dated May 10, 1927. Disclaimer filed November 1, 1935, by the assignee, *M. H. Detrick Company*.

Hereby enters this disclaimer to that part of the claim in said specification which is in the following words to wit:

“5. In a furnace, an ignition arch comprising a plurality of frames having their lower extremities disposed adjacent the fuel inlet and each including a tile supporting portion extending inwardly and upwardly from its lower extremity, said tile supporting portion carrying tile retaining members, and wedge-shaped tile connected at their smaller ends with said retaining members to retain juxtaposed tile with their converging faces in abutment, the larger end surfaces of said tile forming a fire resisting wall extending first inwardly and then abruptly upwardly from the fuel inlet.”

“7. In a furnace, an ignition arch comprising a plurality of collaterally disposed frame members having their lower extremities disposed adjacent and above the fuel inlet, each of said frame members including an inwardly and upwardly extending part carrying tile retaining members, a plurality of wedge-shaped tile engaged at their narrower ends with said retaining members, the tile on each frame member being disposed with the converging faces of juxtaposed tile in abutment whereby the exposed end faces of the tile form a substantially regular convex arch surface extending inwardly and upwardly from the fuel inlet.”

“9. In a furnace, a fire box arch, a transverse suspension beam arranged in front of said arch, and a convex arcuate ignition arch made up of refractory tile suspended from said beam at the front of the fire box chamber, each of said tile presenting but a single face within the combustion chamber.”

“22. In furnace construction, collaterally arranged frame members, wedge-shaped tile suspended thereon with their broader end surfaces exposed within the furnace chamber and their narrower end surfaces exposed outside the furnace chamber, and a wall spaced from the outside ends of the refractories to afford an intervening air duct for circulation of air across said ends of the refractories.”

“24. In a chain grate furnace, the combination with a roof arch over the combustion chamber, of a convex ignition arch suspended at the front of the roof arch and presenting a refractory surface curving inwardly and upwardly from the fuel inlet to accommodate and concentrate heat reflected from the roof arch onto fuel on the grate at the fuel inlet.”
